(57) **CLAIM**

The ornamental design for a door knob as shown and described.

DESCRIPTION

FIG. 1 is a front view of a door knob;

FIG. 2 is a right side view thereof;

FIG. 3 is a left side view thereof;

FIG. 4 is a rear view thereof;

FIG. 5 is a top view thereof;

FIG. 6 is a bottom view thereof;

FIG. 7 is a perspective view thereof; and,

FIG. 8 is a partial enlarged view thereof based on section 8-8 in FIG. 7.

The broken lines in the drawings depict portions of the door knob that form no part of the claimed design.
